Primary Examiner—Wallace R. Burke**Assistant Examiner—Marcus Jackson****Attorney, Agent, or Firm—Krass & Young****[57] CLAIM**

The ornamental design for a portable motion detector, as shown and described.

DESCRIPTION

FIG. 1 is a side perspective view of a portable motion detector showing my new design, with the other side views being identical;

FIG. 2 is a side perspective view thereof, with the detector being shown in a collapsed position;

FIG. 3 is a top plan view thereof; and,

FIG. 4 is a bottom plan view thereof.
